F. W. GRILLICH,
AUTOMATIC FLOOD AND POWER DAM.
APPLICATION FILED NOV. 21, 1921.

Patented Dec. 12, 1922.

INVENTOR.
FREDERICK W. GRILLICH.
BY *Elmer B. Dugay*
ATTORNEY.

UNITED STATES PATENT OFFICE.

FRIDRICH W. GRILLICH, OF INDIANAPOLIS, INDIANA.

AUTOMATIC FLOOD AND POWER DAM.

Application filed November 21, 1921. Serial No. 516,638.

To all whom it may concern:

Be it known that I, FRIDRICH W. GRILLICH, a citizen of Germany, residing at Indianapolis, in the county of Marion and State of Indiana, have invented certain new and useful Improvements in Automatic Flood and Power Dams, of which the following is a specification.

This invention relates to automatic flood and power dam, and the prime feature of the invention is in so constructing the gate portion of the dam that the pressure of the water thereagainst will maintain the gate in an upright, operable position, and which will pivot on its axis in the event the water reaches a certain height above the pivotal point of the gate thereby permitting the water to escape both above and below the gate.

A further feature of the invention is the provision of means for causing the gate to assume its normal upright position as the volume of water recedes so that a constant supply of water is maintained for power or other purposes.

A further feature of the invention is in so constructing the parts of the gate that a very strong and durable structure will be provided while the cost thereof will be maintained at a minimum.

A further feature of the invention is the provision of spring-pressed means for forming a packing at the ends of the gate to prevent undue leakage of water between the gate and its retaining walls.

A further feature of the invention is the provision of means at the lower edge of the gate for forming a seal between the gate and the base portion of the structure.

Other objects and advantages will be hereinafter more fully set forth and pointed out in the accompanying specification.

In the accompanying drawings,

Figure 1 is a top plan view of the combined flood and power dam,

Figure 2 is an elevation thereof,

Figure 3 is a sectional view along the line 3—3, Figure 1,

Figure 4 is an elevation of the inner face of one end wall of the structure,

Figure 5 is an enlarged detail sectional view as seen on line 5—5, Figure 4,

Figure 6 is a detail elevation of the gate removed from its retaining walls,

Figure 7 is an end elevation thereof, and

Figure 8 is a detail top plan view of the gate.

Referring to the drawings, 1 indicates the gate portion of the dam, 2 the supporting abutments therefor, and 3 a base for the abutments, the base and abutments being preferably constructed of a concrete material and built into the bed of the stream, and in the event the stream is of considerable width any number of auxiliary abutments 4 may be provided for supporting a number of gate sections.

The gate portion 1 is preferably constructed of vertically arranged I-beams 5 to the opposite faces of which are attached sheets of metal 6 and to add strength to the gate structure so formed the spaces between the I-beams and the plates on opposite faces thereof are preferably filled with concrete, as best shown at 7 in Figure 8.

Attached to the down stream face side of the gate 1 are bearing blocks 8 through which is extended a rod 9, the ends of said rod pivoting in the abutments, and in order to cause the gate to automatically open when the volume of water has increased to a certain depth, the bearing blocks and rod are positioned below the horizontal axial center of the gate, consequently when the water has reached a certain height the gate will be overbalanced and caused to open sufficiently to permit the excess volume of water to escape. As the volume of water recedes the pressure of the water against the lower portion of the gate will cause the gate to gradually close and shut off the escape of the water, thereby maintaining the volume of water employed for power or other purposes substantially at a uniform flow.

In the event of a flood or the volume of water increases to such an extent as to swing the upper edge of the gate to its extreme position, cushioning springs 10 are entered in pockets 11 in the abutments for engage-

ment with arms 12 at the ends of the gate sections 1, said arms being positioned adjacent the upper edge of the gate section. The springs 10 not only cushion and even-
5 tually stop the swinging movement of the gate section, but serve to raise the top edge of the gate towards a vertical position as the pressure of the water on the gate decreases, the spring serving to elevate the top edge
10 of the gate until the pressure of the water on the lower edge thereof will automatically close the gate when the volume of water has receded to its normal level.

To prevent undue leakage of water below
15 the lower edge of the gate 1, a bar 13 may be partially imbedded in the base 3 with which contacts an inclined flange 14 of an angle plate 15, and as the bar 13 is prefer-
20 ably round in cross section, the flange 14 will readily ride over the exposed face of the bar and form a substantially water tight connection therewith, but such connection will not in any manner interfere with the
25 swinging action of the gate due to the change of volume of water in the stream.

To prevent the passage of water between the ends of the gate and the supporting abutments, sealing pads 16 are provided which press against the ends of the gate and
30 which are supported by the abutments, each sealing pad having a plurality of stems 17 which enter recesses 18 in the abutments, and surrounding these stems are compression
35 springs 19 which force the sealing pads against the ends of the gate. Each sealing pad is provided with a channel 20, the flanges of which enter the recess 18 and prevent the passage of the water between the sealing pads and the faces of the abut-
40 ments.

It will thus be seen that I have provided a comparatively cheap form of flood and power dam and at the same time one that will be extremely strong and durable, and if desired an added number of I-beams may be
45 used at the longitudinal central portion of the gate thereby increasing the strength at the point of greatest strain.

It will likewise be seen that the volume
50 of water used for power and other purposes will be maintained substantially at a uniform flow owing to the automatic operation of the gates both in opening and closing, and by causing the gate to swing with the
55 movement of its upper edge downstream, or with the flow of the water, but very little water will flow over the top edge of the gate and then only in the event the volume of water reaches flood stage, thus avoiding the

usual destructive effect of the water, such as results where the excess volume of water passes over the top of the dam.

Having thus fully described my said invention, what I claim as new and desire to secure by Letters Patent, is:

1. In an automatic flood and power dam, the combination with a base and supporting abutments thereon, of one or more gates between said abutments, means for pivotally connecting the gates with the abutments, 70 an angle plate for forming a seal at the lower edge of the gate, a bar circular in cross section and partly embedded in said base, the exposed portion of said bar being adapted for engagement with one flange of said angle plate, and spring-pressed sealing pads at the ends of the gate.

2. In an automatic flood and power dam, a gate construction comprising a plurality of vertically disposed I-beams, metallic sheets attached to opposite faces of the I-beams, and a concrete mixture introduced between said plates and entirely enclosing said I-beams.

3. In an automatic flood and power dam, the combination with a base supporting abutments having pockets therein, of a gate structure pivotally mounted between said abutments, arms at the ends of said gate, cushioning springs in said pockets adapted to be engaged by said arms for cushioning and controlling the swinging movement of the gate and for returning said gate substantially to its initial position, an angle plate secured at the lower edge of said gate 95 and a bar circular in cross section and partially embedded in said base, the exposed portion of said bar adapted for engagement with one flange of said angle plate for forming a seal.

4. In an automatic flood and power dam, the combination with supporting abutments and a gate structure pivotally mounted between said abutments, of sealing pads between the ends of the gate and said abutments, stems on said pad, cushioning springs for holding the pads against the ends of the gate under pressure, and channel plates carried by the pads adapted to close passage between the sealing pads and the abutments.

In witness whereof, I have hereunto set my hand and seal at Indianapolis, Indiana, this 15th day of November, A. D. nineteen hundred and twenty-one.

FREDRICK W. GRILLICH. [L. S.]
